MUTE FOR A FRETTED STRINGED MUSICAL INSTRUMENT

Rolando Valdes Blain, 72 Barrow St.,
New York, N.Y. 10014

Filed Aug. 29, 1973, Ser. No. 392,540

Term of patent 14 years

Int. Cl. D17—99

U.S. Cl. D56—1 R

FIG. 1

FIG. 2

FIG. 3

FIG. 4

FIG. 5

FIG. 1 is a perspective view of a mute for a fretted stringed musical instrument showing my new design;

FIG. 2 is a left side elevational view, the right side being a mirror image thereof;

FIG. 3 is a bottom plan view;

FIG. 4 is a front elevational view; and

FIG. 5 is a rear elevational view.

I claim:

The ornamental design for a mute for a fretted stringed musical instrument, as shown and described.
